US00D705391S

(12) **United States Design Patent**
Okazaki et al.

(10) **Patent No.:** US D705,391 S
(45) **Date of Patent:** ** May 20, 2014

(54) **DEGASSING AERATION MEMBRANE
MODULE**

(75) Inventors: **Hiroyuki Okazaki**, Toyohashi (JP);
Yoshie Tanizaki, Toyohashi (JP)

(73) Assignee: **Mitsubishi Rayon Co., Ltd.** (JP)

(**) Term: **14 Years**

(21) Appl. No.: **29/431,450**

(22) Filed: **Sep. 7, 2012**

(30) **Foreign Application Priority Data**

Mar. 7, 2012 (JP) 2012-005145

(51) **LOC (10) Cl.** **23-01**

(52) **U.S. Cl.**

USPC **D23/207**

(58) **Field of Classification Search**

USPC D23/207, 209; 96/4, 6; 95/46;
210/467.01

(57) **CLAIM**

The ornamental design for a degassing aeration membrane module, as shown and described.

DESCRIPTION

FIG. 1 is a perspective view of a degassing aeration membrane module showing our new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof; and,
FIG. 7 is a bottom plan view thereof.
